UNITED STATES PATENT OFFICE

2,486,858

HEAVY-DUTY CONTAINER OPENER

Woodward J. May, Pittsfield, Mass., assignor to
 May's Auto Parts, Incorporated, Pittsfield,
 Mass., a corporation of Massachusetts

Application June 17, 1948, Serial No. 33,499

14 Claims. (Cl. 30—15)

1

This invention relates to container openers, and more particularly to a mechanism for opening containers of the cupped head type.

It is now the rather common practice to ship articles such as ammunition and ordinance of various types, instruments, etc., in hermetically sealed containers in which they can remain indefinitely in any climate without rusting or corroding. These containers are of various shapes and sizes. For example, some of the containers are cylindrical but differ greatly in their proportions, while others of the containers are generally rectangular in cross-sectional shape with rounded corners. Containers of this type have cup shaped heads, corresponding in shape to the ends of the containers, and the heads are inserted in position and welded at their edges to the edges of the containers.

While containers of this type are highly effective for the purpose stated, the opening of the containers presents a substantial problem. In the absence of an adequate mechanical device for opening containers of this character, the opening operation usually requires a substantial length of time and results in the destruction of the container so that it can not be salvaged for further use.

An important object of the present invention is to provide a novel mechanism for opening containers of the character referred to wherein the container itself is cut parallel to the top edge thereof below the welded connection of the cap to the container body, thus permitting the cap to be lifted out without destroying the container.

A further object is to provide an apparatus of this character wherein the rotation of a shaft causes the device to travel relatively around the container periphery to cut through the wall thereof adjacent the welded connection of the cap to the container, thus cutting off only the top edge of the container body without destroying the container or otherwise damaging it, whereby the container may be salvaged for further use.

A further object is to provide a device of this character having novel means for cutting through the body of the container, such means being adapted to cut through various materials of different thicknesses to make a clean cut to permit the easy removal of the cap of the container.

A further object is to provide a novel cutting device in a mechanism of this character which is readily adjustable for operation according to the thickness of the material of the container,

2

and to provide in conjunction therewith a stop for limiting the depth of the cut to the proper point.

A further object is to provide a novel apparatus of this character which embodies cutting wheels and driving or gripping wheels so arranged as to secure and maintain the proper relation between the cutting wheels and the flange of the head and the body of the container for the cutting of the latter, and to provide novel mounting means for the cutting wheels whereby the latter automatically assume proper cutting positions regardless of the adjustment of the cutting device in accordance with the thickness of the material of the container.

A further object is to provide novel means for engaging the inner surface of the flange of the cap during the cutting operation to steady the movement of the mechanism around the container as the cutting takes place.

A further object is to provide novel leveling and height adjusting means for the mechanism to predetermine the position of the line along which the cutting operation will take place.

Other objects and advantages of the invention will become apparent during the course of the following description.

In the drawings I have shown two embodiments of the invention. In this showing,

Figure 1 is a plan view of the apparatus, parts being shown in section and parts being broken away;

Figure 2 is a sectional view on line 2—2 of Figure 1;

Figure 3 is a longitudinal sectional view on line 3—3 of Figure 1;

Figure 4 is a detail sectional view on line 4—4 of Figure 1;

Figure 5 is a detail perspective view of the cutting elements and the carrier arm therefor, the parts being shown separated;

Figure 6 is a bottom plan view of the base plate of the device;

Figure 7 is a detail sectional view on line 7—7 of Figure 1;

Figure 8 is a detail perspective view of a combined clamping and leveling device, parts being shown separated;

Figure 9 is a plan view on a reduced scale showing the device in position on the top of a container;

Figure 10 is a fragmentary bottom plan view of the mechanism;

Figure 11 is an enlarged fragmentary face view of one of the gripping wheels;

Figure 12 is a fragmentary bottom plan view of a modified form of the device, parts being broken away; and

Figure 13 is a fragmentary sectional view on line 13—13 of Figure 12.

Referring to Figures 1, 2, 3 and 6, the numeral 10 designates a substantially triangular, relatively heavy base plate to which is welded as at 11 an upstanding housing 12 normally closed by a cover 13 secured in position in any suitable manner, for example by screws 14 (Figure 1). Within the housing 12 are arranged the power driven means for operating the mechanism in accordance with the following description.

Referring to Figure 3, the numeral 18 designates a sleeve seated at its lower end on the base plate 10 and preferably welded thereto as at 19. This sleeve contains a bearing bushing or bearing bushings 20 rotatably receiving a primary drive shaft 21. This shaft projects through an opening 22 in the base plate and this opening is capped as at 23. Between the upper end of the sleeve 18 and the cover 13, the shaft 21 is cut to form a driving pinion 25 for a purpose to be described. The shaft 21 projects through a thrust sleeve 26 in the cover 13 and a bearing 27 rotatably receives the thrust sleeve 26. The shaft projects substantially above the cover 13 and is provided with a preferably substantially square section 28 for connection with a suitable handle indicated in dotted lines by the numeral 29 in Figure 1. The shaft 21 thus may be operated by hand, or the chuck of an electric drill or other power source may be connected to an upper extension 30 on the shaft 21.

A sleeve 34 is welded as at 35 to the base 10 and a bearing bushing 36 is arranged in this sleeve and in an opening 37 in the base 10. This opening is capped as at 38. A shaft 40 is journaled at its lower end in the bushing 36 and is formed with a vertically elongated pinion 41 engageable with gears to be referred to later. At its upper end, the shaft 40 slips into the hub 42 of a gear 43 which meshes with the pinion 25 as shown in Figures 1 and 3. The gear hub 42 may be keyed as at 45 to the shaft 40, and is rotatable in a bushing 46 projecting upwardly into an opening 47 in the cover 13 and into a sleeve 48 welded to the cover 13 as at 49. The opening 47 is capped as at 50.

Referring to Figures 1 and 2, the numerals 55 and 56 designate a pair of shafts, each of which is provided at its lower end with a gripping wheel 57 to be referred to in detail later. The shaft 55 is rotatable in a bushing 58 arranged within a sleeve 59 welded as at 60 to the base 10. The shaft 55 carries a gear 62 meshing with the pinion 41 (Figures 1 and 3). Above the gear 62, the shaft 55 is journaled in a bushing 64. This bushing is arranged in a sleeve 65 welded at 66 to the cover 13, and the opening in the cover 13 in which the bushing 64 is arranged is capped as at 67.

A sleeve 70 contains a bushing 71 in which the shaft 55 is journaled. The sleeve 70 is substantially shorter than the sleeve 59 to provide space for a gear 71, identical with the gear 62, and fixed to the shaft 56. The gears 62 and 71 may be held in position in any suitable manner, for example by snap rings 72 on their respective shafts. The sleeve 59 is cut away as at 73 to provide space for the gear 71, as shown in Figure 2. The gears 62 and 71 are identical as stated, and have their rotational axes equi-distantly spaced from the axis of the shaft 40.

The gear 71 meshes with the pinion 41 in the same manner as, but below, the gear 62.

Referring to Figures 1, 3 and 5, the numeral 80 indicates a cutting mechanism as a whole. This mechanism comprises a channeled body 81 pivotally connected at one end to the base plate 10 by a heavy pivot pin 82. At its opposite end, the body or arm 81 is slotted as at 85 to receive a bolt 86, the outer end of which is threaded in a clamping member 87 operable by a handle-bar 88. The opposite end of the bolt 86 is provided with an eye 89 arranged in a slot 90 formed in a block 91 welded as at 92 to the bottom of the base plate 10. A pin 93 (Figure 1) pivotally connects the bolt 86 to the block 91.

The rotation of the clamping device 87 moves the free end of the arm 81 inwardly for a purpose to be described, and a stop bolt 95 limits such movement. This bolt is provided with a head 96 engaging the arm 81 as shown in Figure 1, and the inner end of the bolt 96 is threaded in the block 91 and fixed in adjusted positions by a lock nut 97.

The cutting of the body of the container in a manner to be further described below is accomplished by a pair of rotary sharp edged cutters 100 carried by stub shafts 101 journaled in a carrier 102. This carrier is substantially U-shaped in cross-section in the center thereof, and a pivot pin 103 extends through the carrier and through the arm 81, suitable openings 104 and 105 being respectively provided in these elements to receive the pin 103.

The device is operable for opening containers of the general character referred to. One of these containers is shown in plan in Figure 9 and in dotted lines in Figure 3, each container comprising a container body 110 and a cupped head 111. The head 111 has an upstanding flange 112 fitting within the upper end of the container wall, and the upper edge of the flange and the upper edge of the container body are welded to each other to hermetically seal the container. It will be obvious in Figure 3 that the cutters 100 are operative to cut through the container body below the weld between the container body and the upper edge of the flange 112.

As will become apparent, the upper edges of the container body and the flange 112 sometimes directly contact with the bottom of the base plate 10. To minimize wear on such plate, the latter has portions of the lower face thereof cut away as at 115 preferably to a depth of about one-eighth of an inch, and this space is filled with any suitable hard material 116, such as hard welding rod electrically welded in the recesses 115.

Means are provided to assist in steadyng the device in its movement around a cylindrical container. One end of the base plate 10 is provided with a slot 120 through which projects a bolt 121 threaded at its upper end as at 122 for reception in a clamping element 123 to be referred to later. At its lower end, the bolt 121 is provided with a two part head, the upper part 125 of which corresponds in thickness to the diameter of the bolt 121 to slide in the slot 120. The lower part of the bolt head, indicated by the numeral 126, is circular. The lower end of the bolt 121 is tapped as at 128 to receive the upper end of an adjusting screw 129 having a lower head 130 engageable under some conditions with the head 111. A lock nut 131 secures the screw 129 in adjusted positions.

A clamp 135 (Figures 3 and 8) is provided with an opening 136 slidable over the bolt 121. The

clamp 135 has a depending flange 137 along one edge engageable with the top of the base 10. The remainder of the bottom face of the clamp 135 is relatively flat except for the provision of a notch 138 receiving a bar 139 resting on the base 10. The depth of the notch 138 plus the depth of the flange 137 is equal to the vertical thickness of the bar 139, and it will be obvious that rotation of the clamping device 123 by a handle-bar 140, provided for this purpose, will clamp the bar 139 in any desired adjusted position.

The bar 139 has its free end overhanging the base plate 10 turned downwardly as at 141 and provided at its lower end with a roller 142. When opening cylindrical cans, the clamp 135 is loosened and the arm 139 is slid endwise in slot 138 to move the roller 142 into engagement with the inner or outer surface of the flange 112. The clamp is then tightened, and in operation, the roller 142 follows around the flange 112 and steadies the operation of the mechanism as further described below. The roller 142 and associated parts possess a further advantage which will be described in connection with the operation of the apparatus.

At each side thereof, the base plate 10 is provided with a block 145, welded to the base 10 as at 146, and preferably also welded to the housing 12. This block is provided intermediate its height with a recess 147 for a purpose to be described. A threaded stem 148 is vertically slidable in openings 149 formed in the block 145, and a knurled adjusting nut 150 is arranged in the recess 147 and threaded on the stem 148. The lower end of the stem 148 is provided with a non-circular head 151 (Figures 4 and 10) arranged in a similarly shaped opening 152 formed in the base plate 10. A knurled lock nut 153 is threaded on the upper end of the stem 148. By loosening the nut 153, the stem 148 may be adjusted vertically and then tightened by screwing down on the nut 153. The head 151 of each of the adjusting devices referred to is adapted to contact the upper face of the container head 111 to level and vertically adjust the device as a whole, being used in conjunction with the adjusting screw 129. This is sometimes necessary because of the depth of the flange 112 of the container head and sometimes because of the substantial curve between the head 111 and flange 112.

As will become more apparent, the gearing in the housing 12 is operable to rotate the gripping wheels 57, and these wheels, gripping against the inner surface of the flange 112, will cause the device to progressively move along the periphery of the container. It is preferred that the gripping wheels be serrated as at 155 to provide teeth slightly flattened at the outer ends as at 156 to prevent the teeth from being too deeply embedded in the flange 112 while at the same time affording an efficient gripping action for the purpose stated.

Except as indicated below, the form of the invention shown in Figures 12 and 13 is the same as that previously described, and corresponding elements have been similarly indicated by reference numerals. The rocking carrier 102 previously described operates to permit the cutting wheels 100 to adjust their engagement with the flange of the container head regardless of the adjusted position of the arm 81 in accordance with the thickness of the material of the container body. In other words, if the cutting wheels were bodily immovable relative to the arm 81, the condition would exist wherein one cutter travels

through an arc of longer radius than the other cutter. This condition would result in one cutter doing all or most of the cutting on cans of different diameters and different thicknesses. In this form of the invention, the arm 81 (Figure 13) is carried by a pivot pin 161 which is substituted for the straight pivot pin 82 previously described. The pin 161 is provided with a flange 162 arranged between the arm 81 and base plate 10, and above this flange, the upper end 163 of the pivot pin is eccentric to the lower end thereof. By engaging the upper end of the pivot pin with a suitable tool, the pin may be turned to adjust the position of the pivot axis of the lower pin portion 161, and the pin may be fixed in the proper adjusted position by the set screw 164. In this way, the arm 81 and cutting wheels 100 are properly adjusted according to the thickness of the material of the container.

20

Operation

When it is desired to remove the head from a container of the type referred to, the device is placed in position over the head and the leveling and adjusting screws 129 and 148 are vertically adjusted, if necessary to place the apparatus at the proper height, level and parallel to the head 110. If a circular container is to be opened, the arm 139 is adjusted and clamped in proper position with the roller 142 engaging the inner or outer surface of the container head flange 112 with the gripping wheels 57 engaging the flange 112 of the container. The arm 139, while unclamped, may be moved into adjusted position with some force, for firmly seating the gripping wheels 57 against the flange 112. The foregoing operations preferably take place with the arm 81 open. By rotating the clamping device 87 to loosen it, the bolt 86 may be swung out of the notch 85 so that the arm 81 can be swung outwardly. When the parts have been placed in the position described above, the arm is closed, whereupon the bolt 86 is replaced in operative position and the clamp 87 rotated until the edges of the cutting wheels 100 are forced through the material of the container body 110 and preferably partially into the flange 112 to insure the complete clean cutting of the container body 110 entirely therethrough. If the material of the container body is relatively hard and the foregoing operation is found too difficult, it may be performed progressively while moving the apparatus around the container in the manner described below.

The handle 29 is rotated, or suitable power means is employed for rotating the shaft 21, this shaft being rotated in the proper direction to cause the clamping wheels 57 to rotate counter-clockwise as viewed in Figures 10 and 11. Rotary motion is transmitted from the pinion 25 to the gear 43, thence from the pinion 41 to both of the gears 62 and 71 to simultaneously rotate the gripping wheels 57 in the same direction and at the same speed. Pressure having been applied to the cutting wheels to at least partially embed them in the wall of the container, the upper end of the container wall and the flange 112 will be gripped between the wheels 57 and the cutting wheels 100, and the gripping wheels 57 will cause the device to progressively travel relatively around the container. During such movement, the handle-bar 88 (Figure 1) can be rotated to complete the movement 75 of the cutting wheels through the body of the

container, if this operation has not been previously accomplished.

Movement of the apparatus around the container takes place completely through 360° , or slightly more if movement of the apparatus around the container is depended upon to assist the cutting wheels in completely penetrating through the container body. This operation of moving the apparatus around the container takes place with the cutting wheels moving perfectly horizontally, and accordingly, the upper portion of the container body below its welded connection to the head 111 will be completely cut through, thus permitting the head 111 to be easily removed. The container will be left with a smoothly cut upper edge, except for the removal of the extreme upper end of the container body, the container will be undamaged and may be salvaged for further use.

The depth of the cutting of the wheels 100 is regulated by the stop screw 95 in each form of the invention. This screw is positioned to engage the arm 81 at such a point that the wheels 100 will have cut entirely through the container body and partially through a flange 112. By following this procedure, the smooth and complete cutting through the container body is assured.

The apparatus may be used with cylindrical containers of widely differing sizes and proportions. It also may be used with containers of shapes other than round provided the corners are curved on a radius of, for example, at least two inches. The apparatus is readily set up and easily and quickly operated, and has been found in practice to act efficiently as a heavy duty portable container opener, the use of which requires little or no skill and does not damage the relatively expensive containers.

While it has been generally described that the present device travels around the periphery of the container, it will be obvious that the device itself may be anchored with the container rotatable during the cutting operation. It is understood, therefore, that where reference is made in the claims to movement of the device around the container, this expression defines relative movement rather than specific movement of the device with the container remaining stationary.

I claim:

1. An opener for containers having cupped heads provided with upstanding flanges fitting within the container bodies and secured thereto at the upper edge thereof, comprising a body, a pair of gripping wheels carried by said body and engageable against the inner face of said flange, a pair of cutting wheels engageable against the outside of the container body respectively opposite said gripping wheels, means for clamping said cutting wheels toward said gripping wheels to cause said cutting wheels to penetrate through the container body, and means for simultaneously rotating said gripping wheels in the same direction to cause them to travel, together with said cutting wheels, around the container body to completely sever the upper edge thereof.

2. An opener for containers having cupped heads provided with upstanding flanges fitting within the container bodies and secured thereto at the upper edge thereof, comprising a body, a pair of gripping wheels carried by said body and engageable against the inner face of said flange, a pair of cutting wheels engageable against the outside of the container body respectively opposite said gripping wheels, means for clamping

said cutting wheels toward said gripping wheels to cause said cutting wheels to penetrate through the container body, means for limiting the movement of said cutting wheels toward said gripping wheels, and means for simultaneously rotating said gripping wheels in the same direction to cause them to travel, together with said cutting wheels, around the container body to completely sever the upper edge thereof.

3. An opener for containers having cupped heads provided with upstanding flanges fitting within the container bodies and secured thereto at the upper edge thereof, comprising a body, a pair of gripping wheels carried by said body and engageable against the inner face of said flange, an arm pivotally connected to said body to swing toward and away from said gripping wheels, a pair of cutting wheels carried by said arm and movable into engagement with the container body at points respectively opposite said gripping wheels, means connected between said body and said arm for moving the latter toward said gripping wheels to cause said cutting wheels to penetrate through the container body, and means for simultaneously rotating said gripping wheels in the same direction and at the same speed to cause said gripping wheels, said arm and said cutting wheels to travel around the container body and completely sever the upper edge thereof,

4. An opener for containers having cupped heads provided with upstanding flanges fitting within the container bodies and secured thereto at the upper edge thereof, comprising a body, a pair of gripping wheels carried by said body and engageable against the inner face of said flange, an arm pivotally connected to said body to swing toward and away from said gripping wheels, a pair of cutting wheels carried by said arm and movable into engagement with the container body at points respectively opposite said gripping wheels, means connected between said body and said arm for moving the latter toward said gripping wheels to cause said cutting wheels to penetrate through the container body, adjustable means carried by said body and engageable with said arm to limit movement of said cutting wheels toward said gripping wheels, and means for simultaneously rotating said gripping wheels in the same direction and at the same speed to cause said gripping wheels, said arm and said cutting wheels to travel around the container body and completely sever the upper edge thereof.

5. An opener for containers having cupped heads provided with upstanding flanges fitting within the container bodies and secured thereto at the upper edge thereof, comprising a body, a pair of gripping wheels carried by said body and engageable against the inner face of said flange, an arm pivotally connected to said body to swing toward and away from said gripping wheels, a pair of cutting wheels carried by said arm and movable into engagement with the container body at points respectively opposite said gripping wheels, means connected between said body and said arm for moving the latter toward said gripping wheels to cause said cutting wheels to penetrate through the container body, means for effecting bodily adjustment of said cutting wheels relative to the container body whereby said cutting wheels are adapted to uniformly cut through the container body, and means for simultaneously rotating said gripping wheels in the same direction and at the same speed to cause said gripping

wheels, said arm and said cutting wheels to travel around the container body and completely sever the upper edge thereof.

6. An opener for containers having cupped heads provided with upstanding flanges fitting within the container bodies and secured thereto at the upper edge thereof, comprising a body, a pair of gripping wheels carried by said body and engageable against the inner face of said flange, an arm pivotally connected to said body to swing toward and away from said gripping wheels, a pair of cutting wheels carried by said arm and movable into engagement with the container body at points respectively opposite said gripping wheels, means connected between said body and said arm for moving the latter toward said gripping wheels to cause said cutting wheels to penetrate through the container body, means for connecting said cutting wheels for pivoted turning movement relative to said arm on an axis parallel to the pivot axis of said arm whereby said cutting wheels are bodily movable about the pivot axis of said arm to uniformly cut through the container body, and means for simultaneously rotating said gripping wheels in the same direction and at the same speed to cause said gripping wheels, said arm and said cutting wheels to travel around the container body and completely sever the upper edge thereof.

7. An opener for containers having cupped heads provided with upstanding flanges fitting within the container bodies and secured thereto at the upper edge thereof, comprising a body, a pair of gripping wheels carried by said body and engageable against the inner face of said flange, an arm pivotally connected to said body to swing toward and away from said gripping wheels, a pair of cutting wheels carried by said arm and movable into engagement with the container body at points respectively opposite said gripping wheels, means connected between said body and said arm for moving the latter toward said gripping wheels to cause said cutting wheels to penetrate through the container body, the pivotal connection of said arm to said body comprising a pivot point having portions engaging said body and said arm arranged eccentric to each other, means for fixing said pivot pin in adjusted rotary positions to vary the cutting action of said cutting wheels according to the thickness of the container body, and means for simultaneously rotating said gripping wheels in the same direction and at the same speed to cause said gripping wheels, said arm and said cutting wheels to travel around the container body and completely sever the upper edge thereof.

8. An opener for containers having cupped heads provided with upstanding flanges fitting within the bodies of the containers and secured thereto at the upper edges of the container bodies, comprising a plate adapted to be arranged over and parallel to the container head, a pair of gripping wheels rotatably supported by said plate and engageable against the inner face of the flange of the container head, a gear fixed to each gripping wheel, a cutting wheel arranged outwardly of the container and engageable with the container body at a point opposite each of said gripping wheels, means for forcing said gripping wheels toward the container to cause them to penetrate therethrough, and means for rotating said gripping wheels at the same speed and in the same direction to cause them to travel around the container together with said cutting wheels,

comprising a single pinion meshing with both of said gears.

9. Apparatus constructed in accordance with claim 8 provided with vertically adjustable means 5 carried by said plate at spaced points and engageable with the head of the container to level said plate relative to the container head.

10. Apparatus constructed in accordance with claim 8 provided with means carried by said plate 10 for adjustably determining the extent of penetration of said cutting wheels through the container body.

11. An opener for a container having a cupped head including a relatively flat body and an upstanding flange fitting within the top of the container body and fixed thereto at the upper edge thereof, comprising a plate adapted to be arranged over the body of the container head, a pair of gripping wheels rotatably carried by said plate 15 and rotatable on parallel vertical axes in engagement with the inner surface of the flange of the container head, an arm pivotally connected at one end to said plate and having a free end portion arranged outwardly of and movable toward and away from the container body, a wheel 20 supporting member carried by said arm adjacent the free end thereof and connected thereto for turning movement relative thereto on a vertical axis, a pair of cutting wheels carried by said 25 wheel supporting member and movable by said arm inwardly to positions engaging the container body at points respectively opposite said gripping wheels, means connected between said plate and said arm for forcing the latter inwardly toward 30 the container body to cause said cutting wheels to penetrate through the container body, and means for simultaneously rotating said gripping wheels in the same direction and at the same speed to cause said cutting wheels, said arm and 35 said gripping wheels to move around the container and completely sever the upper end of the container body.

12. Apparatus constructed in accordance with claim 11 provided with an adjusting screw carried by said plate, said screw projecting toward 45 and engaging said arm adjacent the free end thereof to limit the movement of said arm toward the container body and thus limit the extent of movement of said cutting wheels toward said 50 gripping wheels.

13. Apparatus constructed in accordance with claim 11 provided with a plurality of vertically adjustable screws carried by said plate and movable downwardly into engagement with the body 55 of the container head to level said plate relative thereto.

14. An opener for a cylindrical container having a cupped head comprising a horizontal body and an upstanding cylindrical flange fitting within the 60 top of the container body and secured thereto at the upper edge thereof, comprising a plate adapted to be arranged over the body of the container head, a pair of gripping wheels carried by said plate and rotatable on parallel vertical axes in engagement with the inner face of 65 said flange, cutting wheels supported with respect to said plate radially outwardly of and respectively opposite said gripping wheels, means for forcing said cutting wheels toward said gripping 70 wheels to cause said cutting wheels to penetrate through the container body, means for simultaneously rotating said gripping wheels at the same speed and in the same direction to cause said cutting wheels and said gripping wheels to 75 move around the container to completely sever

11

the upper end of the container body, a bar projecting from said plate, a roller carried by said bar, and means for clamping said bar to said plate in adjusted positions with said roller in engagement with the inner face of said flange at a point circumferentially remote from said gripping wheels.

WOODWARD J. MAY.
